P. ESSER

WALKING TOY

Filed March 20, 1923

UNITED STATES PATENT OFFICE.

PETER ESSER, OF CLIFTON, NEW JERSEY.

WALKING TOY.

Application filed March 20, 1923. Serial No. 626,291.

To all whom it may concern:

Be it known that I, PETER ESSER, a citizen of the United States, and a resident of Clifton, in the county of Passaic and State of New Jersey, have invented certain new and useful Improvements in Walking Toys, of which the following is a specification.

This invention relates to improvements in toys and particularly to types having self-containing driving means by which their movable parts are actuated.

One of the objects of the invention is to provide a toy, simulative of a human figure, the legs of which are caused to advance the figure, step by step along a surface, thus closely resembling a person in the act of skating.

Another purpose is to produce a mechanical toy capable of maintaining its equilibrium while advancing.

A further aim is in the provision of a toy, representing a skater provided with a staff or hockey stick and arranged to swing one of its arms in unison with the leg movement, the driving mechanism being wholly contained interiorly of the figure, obscured from view and guarded from ordinary injury.

These several aims, objects and purposes are accomplished by the novel construction, combination and arrangement of parts hereafter described and shown in the accompanying drawing, forming part of this disclosure, and in which:—

Figure 1 is a front view of an embodiment of the invention.

Figure 2 is a side view of the same, parts being broken away to disclose the construction.

Figure 3 is a fragmentary front elevational view of the operative mechanism as contained within the body of the figure.

In the illustrations the doll-like object is represented as composed of a body, designated by the numeral 10, a head 11, arms 12 and 13, legs 14 and 15 and feet 16 and 17.

These elements are preferably made hollow, of thin sheet metal, shaped and colored to agree with the object depicted.

The arm 12 is connected to the body by a pivot 18 being otherwise rigid and bent to assume the ordinary position of a person's arm in walking.

Both legs are engaged upon a common pivot pin 19 passed through the lower part of the body or, more exactly, the blouse or

garment represented as covering the body, at a point near its lower edge central of the object, thus permitting the legs to swing freely back and forth.

Joints are omitted at the knees and the lower ends of the legs are attached by pivots 20 and 21 to the feet 16 and 17 represented as being encased in shoes.

These shoes are firmly secured upon the lower surfaces of hollow elements 22 and 23 representing skates, having upturned pointed fronts, each being supported by a pair of rollers 24 and 25 pivoted upon pins 26 and 27 fixed transversely in the skate body.

The rear rollers 25 are considerably larger in diameter than the front rollers 24 and have fixed to their sides ratchet wheels 28 engaged by pawls 29 loosely pivoted in the skate bodies near their upper rear corners, as shown in Fig. 2.

Extending outward through the side of the body, to which the fixed arm 13 is attached, is a stem 30 having a thumb knob 31 on its outer end, its inner end being operatively engaged with a winding device for a flat spiral spring contained in the casing 32 secured within the body.

This spring acts as a motor for energizing a gear 33 meshing with a pinion 34 fixed on a spindle 35 having opposed cranks 36 and 37 at its opposite ends and revoluble in the clock works frame comprised of elements 51 and 53 fixed in the body and carrying the spring casing 32.

The leg 15 is formed with an extension 38 reaching from its outer side into the body and contains an appropriate aperture 41 to receive the crank 36, the extension being offset at the point 39 to clear the stem 30.

A similar but longer extension 40, formed with the leg 14, is engaged in a like manner by the crank 37, thus actuating the legs alternately in opposed relation, the shape of the apertures being such as to produce an effect on the legs closely simulative of walking.

Rigid on the spindle 35 is a gear 42 driving a pinion 43 fixed on a spindle 44 having fast upon it a gear 45 driving a pinion 46 rigid on another spindle 47 carrying the fan 48 which acts as a regulator in restraining the speed within a reasonable limit.

The upwardly reaching portion of the leg extension 40 contains a slot 49 in which operates a pin 50 fixed in a crank 52 secured to the pivot 18 the inner end of which is

journalled in the frame 51 and the outer end, passing through the body casing 10, has rigidly attached to it the movable arm 12, causing the arm to oscillate in unison with the leg.

Fixed to the rigid arm 13 is a staff 54 representing a hockey stick and having in its bottom a roller 55 adapted to glide over the surface, slightly raising the stick from the ground, the roller being held in a fork or clevis 56, having its stem 57 pivoted in a vertical plane in the front extending end of the stick 54, acting in the manner of a castor.

15 In operation the spring motor being wound, the toy is placed on any level surface whereupon first one skate and then the other is advanced, the rollers facilitating forward movement and the stick carried roller moved quite regularly forward in advance of the object.

20 Due to the pawl and ratchet action the skates, and hence the object, cannot move rearwardly, but each foot maintains its position while the other is moving forward.

25 As the feet are relatively widely spaced and the staff roller is laterally spaced at side, the object retains its equilibrium with ease, further assisted by maintaining a low center of gravity; and, the staff may be turned in the hand to produce a circular movement of the object if desired.

30 It will be obvious that the invention is not confined to the exact object depicted as it is applicable to a wide range of mechanically operated toys, and further, that while certain preferred embodiments of this device have been shown and described, it will be understood that changes in the form, 35 arrangements, proportions, sizes and details thereof may be made without departing from the scope of the invention as defined in the appended claims.

40 Having thus described my invention, what I claim as new and desire to secure by Letters Patent, is:—

45 1. A toy simulative of a living object, comprising a hollow body, a motor therein, a pair of legs pivoted to the body, said legs having inreaching extensions, a spindle actuated by said motor, said spindle having a crank at each end operatively engaged in its respective leg extension, a pair of rollers at the free ends of each leg, a ratchet wheel 50 associated with one roller in each pair, an arm pivoted to said body, means operated by one of said leg extensions for oscillating said arm, a fixed arm on said body, a staff at the end of said fixed arm extending in advance of the body, and a roller in said staff to rest upon the surface over which the object moves.

55 body one of said arms being pivoted and the other rigid, a support carried by the rigid arm, means for swinging said pivoted arm in synchronism to the movement of one of said legs, rollers at the ends of said legs, and means to prevent certain of said rollers from moving in a reverse direction. 60

65 2. A toy simulative of a living object, comprising a body, a pair of legs pivoted to the body, feet pivoted to the legs, hollow casings representing skates secured to the feet, a single pair of rollers arranged in tandem in each skate, means preventing reverse movement of certain of said rollers, means at the side of the body to prevent tipping and means disposed within said body alternately oscillating said legs. 70

75 3. A toy simulative of a living object, comprising a hollow body, a motor therein, a pair of rigid legs pivoted to the body, said legs having inreaching extensions of unlike length, a foot connected by a single pivot to each leg, elements representing skates fixed on each foot, a pivoted arm on said body operable by the longer of said leg extensions, a fixed arm, a staff carried at the end of the rigid arm, said staff having a forwardly projecting base, a castor in the base of said staff, motor connections for alternately advancing said legs, and means in the skates preventing the legs from moving backward, said means compelling a forward movement of said body as each leg is advanced. 80

85 4. A toy simulative of a living object, comprising a hollow body, a motor therein, a pair of legs pivoted to the body, said legs having inreaching extensions, a spindle actuated by said motor, said spindle having a crank at each end operatively engaged in its respective leg extensions, a pair of rollers at the free ends of each leg, a ratchet wheel 90 associated with one roller in each pair, an arm pivoted to said body, means operated by one of said leg extensions for oscillating said arm, a fixed arm on said body, a staff at the end of said fixed arm extending in advance of the body, and a roller in said staff to rest upon the surface over which the object moves. 95

100 In testimony whereof I have signed my name to this application.

PETER ESSER.
